SCREENING DEVICE

Charles S. Lincoln, Wauwatosa, Wis., assignor to
Allis-Chalmers Manufacturing Company, Milwaukee, Wis., a corporation of Delaware

Application March 13, 1931, Serial No. 522,354

11 Claims. (Cl. 209—326)

This invention relates in general to the art of vibratory screen separators and relates more specifically to an improvement in a single drive shaft screening device provided with an eccentric 5 having means for mounting a single screen or a plurality thereof and arranged to impart vibratory movement to said screen.

More specifically this invention has for one of its objects to provide a resilient rod support for 10 an end portion of the screen of a vibratory screening device as related above, said rod support permitting a ready adjustment of the inclination of the screen with respect to a frame on which the vibratory drive shaft and means cooperating 15 therewith is carried.

Another object of the invention is to provide a vibratory screening device as related above and having a substantially rectangular frame supported by resilient means and having a motor for 20 driving the vibratory shaft thereof mounted at one side of said frame with counter-weights attached to an opposite side of said frame to counterbalance the effect of said motor and related elements and to maintain the eccentric drive 25 shaft in the desired horizontal position.

Another object of the invention is to provide a single shaft vibratory screening device adapted to carry one or a plurality of screens with improved balancing flywheels having adjusting 30 means for selectively counterbalancing the screening device to compensate for the particular number of screens carried by the screening device.

Another object of the invention is to provide a vibratory screening device with improved bearings for carrying the vibrating shaft mechanism, attached to the vibrating screen body thereof and to the supporting frame through the use of ball and socket, self-aligning housings surrounding the anti-friction bearings in which the vibrating shaft mechanism operates.

Another object of the invention is to provide a vibratory screening device, preferably having a supporting frame, a vibrating shaft mechanism rotatably associated with said frame, and having a 45 screen body secured at substantially its mid-length to said vibrating mechanism in a manner permitting the dissociation of the vibrating shaft mechanism as a unit from the device without dismantling or disturbing the screen body.

Another object of the invention is to provide a transverse spring rod end-support for a single drive shaft type of vibratory screening device which is simple in construction, durable and effective in accomplishing the desired results.

Other objects and advantages of the present

invention will be apparent from a consideration of the detailed description and of the drawings accompanying the specification and forming a part thereof on which like or similar reference characters designate the same or similar parts or elements throughout the various views.

Fig. 1 is a plan view of a vibratory, single-drive shaft screening device having the improved resilient rod support associated with an end portion of the vibratory screen thereof.

Fig. 2 is a side elevation of the device shown in Fig. 1 and clearly illustrates the resilient suspension means connected to the four corners of the rectangular frame of the device.

Fig. 3 is a vertical cross-sectional view taken 15 along line III—III of Fig. 1, looking in the direction of the arrows.

Fig. 4 is a sectional detail view of the means for 20 adjustably securing the resilient rod support to the vibratory screen, taken along line IV—IV of Fig. 3, looking in the direction of the arrows.

Fig. 5 is a vertical central broken cross-section taken along line V—V of Fig. 1, looking in the direction of the arrows.

Fig. 6 is an elevational view of a flywheel shown 25 on the eccentric drive shaft in Fig. 5 and shows the balancing plates attached thereto in dot-dash lines.

Fig. 7 is an elevational view of a modified form 30 of flywheel assembled for three screen or three deck operation of the improved vibratory screening device.

Fig. 8 is a cross-sectional view of the flywheel taken on the broken line VIII—VIII of Fig. 7.

Fig. 9 is a view of a portion of a side plate of the 35 screen body taken substantially in the plane of Fig. 5 and shows a modified form of means for detachably securing a reenforced screen within the screen body while simultaneously permitting of the tensioning or stretching of the screen elements in the transverse direction.

Fig. 10 is a partial plan view of the spring rod as 40 shown in Fig. 1 modified in this that a plurality of intermediate clamping means for clamping the spring rod to the vibratory screen body are provided.

Fig. 11 is a fragmentary side view of the frame portion of the screening device shown in Fig. 1 provided with resilient means for supporting the frame at its four corners from an inclined rigid 50 support.

Fig. 12 illustrates the eccentric bearing portion with respect to the remaining concentric portions of the drive shaft 18, said figure being referred to Fig. 5 and being illustrated as showing 55

the relation when the shaft 18 is viewed looking in the line of its axis from the left end of Fig. 5. Reference numeral 34 designates a rectangular frame shown including structural steel I-beam side members 11 and the end members thereof may be L-bars connected by gusset plates at the ends to form a rigid frame. On the frame 34 is mounted at one side thereof, a motor 41 having a drive sheave which receives a plurality of end less V-belts 65 for driving a sheave 31 fixed to one end of an eccentric drive shaft 18 having end bearing portions securing the shaft rotatably with respect to the frame 34. These end bearings comprise outer roller bearing base members 1, cooperating roller bearing caps 2, self-aligning roller bearing housings 3, inner sealing plates 4, an outer sealing plate 58 shown at the left in Fig. 5, an outer bearing cover 5, outer roller bearing spacing collars 6, a retaining washer 19 at each end of the shaft, a roller bearing 8 at the left end of the shaft, see Fig. 5, of the floating type, a corresponding roller bearing 47 at the right end of the shaft 18, of the retainer ring locating type. A sleeve 30 spaces the sheave 31 from the adjacent spacing collar 6, and said bearings are provided with openings at 1 to receive "Alemite" or other suitable fittings for lubricating the same. Adjacent the outer bearing portions of the drive shaft 18 are flywheels 20 designed and provided with means for counterbalancing the effect of the eccentric mounting of the drive shaft and the screen body eccentrically carried thereby, and including means for detachably and selectively receiving balancing blocks 21 to adjust said counterbalancing in accordance with the number and weight of screens carried within the screen body. These flywheels will later be described in detail.

Portions of the shaft 18 inwardly of the flywheel shaft portions are provided with eccentric journals having their throws in the same direction which is illustrated as being downwardly in Fig. 5. The bearing for each eccentric of the drive shaft 18 includes an eccentric roller bearing base 9, an eccentric roller bearing cap 10 and a self-aligning roller bearing eccentric housing 11. The eccentric bearings are held spaced, in conjunction with innermost shoulders on the shaft 18, by a sealed spacing tube 14 surrounding the shaft 18. The spacing tube 14 has integrally formed therewith, as by welds 300, annular flanges 104 engaging with adjacent ends of eccentric bearings 15 and 16 and engaging with the self-aligning roller bearing housings 11 to which housings the flanges 104 are bolted, by bolts not shown, to prevent all foreign matter from reaching the eccentric bearings, which bearing ends are located closest to the atmosphere most highly saturated with foreign fine materials about the screen. The spacing collars 13 on the shaft 18 space also each flywheel 20 from the adjacent eccentric roller bearing. Reference numeral 12 represents eccentric roller bearing sealing plates cooperating with the spacing collars 13. The eccentric roller bearing 15 shown at the left in Fig. 5 is preferably of the locating type whereas the similar eccentric roller bearing 16 shown at the right of Fig. 5 is preferably of the floating type. Reference numeral 59 designates the eccentric roller bearing inner spacing collars which about the innermost shoulders of the shaft 18, the shaft being eccentric only in those portions between these innermost shoulders and the shoulders thereof against which the hubs 95 of the flywheels 20 are shown to abut in Fig. 5.

The screen 73 of which a plurality, parallelly spaced, are shown on the figures are carried through means of certain elements, later to be described, by the eccentric roller bearings on the drive shaft 18. In short, the screens 73 may be said to be mounted within a screen body 22 which partakes of the gyratory movement set up by the eccentric drive shaft 18 which participates in its support. The screen body 22 comprises spaced side plates 23 carrying at the upper portions thereof and attached to their outer faces angle irons or bars 74. The side plates 23 are suitably reinforced transversely by means of spaced stiffening irons 81. Within the screen body in spaced relation and rigidly attached thereto are pairs of side angle irons 85, forming slides for the screen frames 24 and 60. The pairs of angle irons support an upper coarse wire screen 73 and a lower fine wire screen 73, the screens being slid into the screen body 22 from the low end thereof. The opposite end of the screen body may be closed. In order to facilitate ready removal of the screens 73 the screen frames 24 and 60 to which the screens 73 are secured by means of side screen frame bars 29 clamped by means of bolts to the screen frame, are held in place by means now to be described. The side plates 23 of the screen body may be provided with struck-out right angular portions 83 each portion having a vertical slot 84 in one leg thereof for adjustably receiving, to take care of varying thicknesses of screens 73, a carriage bolt 26 carrying a screen frame clamping bar 25 engaging at its lower edge a frame bar 29 and at its upper edge an inner surface portion of the screen body. From this it is evident that by driving home the nuts on the carriage bolts 26 the screen frames 24 and 60 will be rigidly yet detachably supported within the screen body 22. It is, of course, understood that instead of pressing out these right angular portions from the side walls 23 that the same may be provided with openings properly located to be covered by short angle irons 86, preferably welded to the side plates 23, and serving the same purpose as the shown struck-out angular portions 83 in Fig. 5. A modified means for readily securing the screens 73 within the screen body is shown in Fig. 9. This means contemplates a screen having slotted screen reinforcing side members 89 between which and a pair of bars 29 the side portions of a screen 73 are clamped by means of suitable bolts, the slots in members 89 being provided so that the heads of the clamping bolts are entirely within the cross-section of said members 89 and free from the angle irons 85. A short angle iron 86 having a vertical slot 84 in the lower leg member thereof is positioned to cover each opening in the side plates being preferably welded thereto, said slotted leg portion adjustably receiving, to take care of varying thicknesses of screens 73, a carriage bolt 26 having on it a combined clamping and tensioning bar 87. Each clamping bar 87 is provided with a lug 88 welded thereon which precludes the lower end portion of a bar 87 from gouging into the screen 73 when the nuts on the carriage bolts 26 are driven home, to rigidly hold the side members 89 against the supporting angle irons 85, while permitting the tensioning of the screen elements 73 by reason of the outward sliding movement of said side members 89 on the angle irons 85.

Another feature of this invention resides in that the angle irons or bars 74 secured to the upper outer surface portions of the screen body-side plates 23 detachably receive the eccentric

shaft bearing and housing portions to which these parts are attached by means of through bolts 79. The eccentric drive shaft 18 and parts rotating therewith, or in other words the vibrating shaft mechanism is therefore detachable as a unit without disturbing or dismantling the screen body 22. The outer bearings for the shaft 18 are similarly secured to the frame 34 by means of bolts 82, so that the vibrating shaft mechanism may readily be detached as a unit from both the screen body 22 and from the frame 34 without disturbing or dismantling the screen body. Reference numeral 80 designates locating bolts for the eccentric bearings.

15 The vibrating shaft mechanism suspending the screen body 22 at substantially its mid-length from the frame 34 would make the screen body tend to turn with respect to the frame 34. In order to prevent this relative rotation the improved spring rod support which constitutes an important feature of this invention is provided either at the feed end of the screen body or at its discharge end as shown on the drawings or at both ends. Now referring especially to Fig. 3 and 20 4 in which the arrangement of the improved spring rod support means for adjustably and resiliently supporting an end portion of the screen 73 from the frame 34 is shown in detail. The side plates 23 adjacent the low end and 25 inner upper portions thereof are provided with angle irons 64 which support an angle iron cross-piece 62 substantially in the plane defined by the parallel upper edges, the side plates 23 or above said plane to allow of sufficient clearance for 30 large materials to be discharged from the screen. The flange thereof which engages the angle irons 64 is directed away from the shaft 18 and the upwardly directed flange of the angle iron cross-piece 62 is secured to a spring rod 35 through 35 means to be described later. An adjusting plate 63 is substantially centrally secured to the cross-piece 62 and is provided with a vertical slot and the upwardly directed flange of the angle iron cross-piece 62 is provided with cut-away portions 40 bounding said slot to receive a spring rod clamping 45 block plate 38. It is to be understood, however, that the separate adjusting plate may be formed as an integral part of the angle iron 62 by extending its height, thus eliminating a separate element. The central portion of the spring rod 35 is shown provided with clamping blocks 36 grooved to receive the spring rod 35. The portion of the rod 35 within the blocks 36 is preferably surrounded by a rubber or other resilient 50 sleeve 76 and permits of a clamping action on the rod 35 by means of clamping bolts 72 received within transverse bores in the blocks 36 to effect said clamping action. The bolts 72 carry the plate 38 which is sufficiently large to lap the slot in the adjusting plate 63 and to permit of a secure 55 fixation of the clamping blocks 36 to said adjusting plate 63 when the nuts on the bolts 72 are driven home. A pair of collars 39 retained on the rod 35 by set screws is provided on the intermediate portion of the rod 35 to prevent endwise movement of the rod 35 and to prevent displacement of the sleeve 76 within the blocks 36. The end portions of the spring rod 35 are supported from frame 34 by means of clamping 60 blocks 37 which may be integral rectangular steel blocks, also provided with rubber or other resilient sleeves 76 directly receiving the rod 35, secured to the I-beams 74. Each end of the rod 35 is similarly provided with a pair of collars 40 screw 65 set on the rod and located adjacent the sides of 70 75

the blocks 37 to also prevent endwise movement of the rod 35 and to prevent displacement of the rubber sleeves within the blocks 37.

The width of the screen body may be such as to make it desirable to have a plurality of intermediate clamping connections between spaced adjusting plates 63 forming a part of the screen body 22, and the spring rod 35. Such an arrangement is clearly illustrated in Fig. 10. In this way a sufficiently resilient support may be provided for a screen body extended in width, without necessarily increasing the diameter of the spring rod as is apparent.

10 The operation of the spring rod 35 and how it permits closed circuit vibrations at the end portions of the screen to conform closely to the gyroscopic circular closed circuit movements of the eccentric bearings on the drive shaft 18 is readily apparent from the above description of the gyroscopic screening device, as well as is the means 15 cooperating with the spring rod support for permitting the ready adjustment of the inclination of the screen body 22 and therefore also the upper and lower screens 73 with respect to the supporting frame 34.

20 Now referring to Fig. 6 in which a flywheel 20 mounted on shaft 18 in Fig. 5 is shown in side elevation. Fig. 5 shows, as stated before, the eccentric throw in the downward direction and therefore the flywheels have their heavy portions 25 above the center of the shaft 18 and Fig. 6 is a related showing and therefore the radially enlarged rim portion 92 of the rim 91 of flywheel 20 is shown at the top. The web portion 90 intermediate the rim 91 and the hub 95 is provided 30 with three relatively large circular bores 96 whose centers may be on the same circle. The intermediate bore has its center in a diametrical line passing through the keyway 197 in the hub, the keyway being shown located diametrically opposite the throw of the eccentrics. The centers of the bores 96 at each side of this intermediate bore are spaced equal distances from said diametrical line and are therefore necessarily spaced equal distances from a diametrical line at right 35 angles to said diametrical line. Each flywheel 40 is provided with stops or abutments 97 at each side of the intermediate bore 96 and has slots 98 to permit satisfactory casting and subsequent 45 machining of said abutments, so that the plane 50 surface edges of rectangular balancing plates 21 may firmly engage corresponding plane surfaces machined on these abutments. There are abutments on each side of the web 90 and a pair of like balancing plates cooperates simultaneously 55 with the abutments 97. The radially enlarged rim portion 92 also provides a pair of abutments 94 at each side of the web 90 and these are outlined by an elongated slot 93 to likewise permit 60 satisfactory casting and subsequent machining of said abutments and to similarly secure a complete and firm engagement therewith of edges of the rectangular balancing plates 21. The bores 96 are provided to enhance the unbalance of the flywheels without adding to their weight. The 65 operation of this form of flywheel is as follows: With no balancing plates 21 bearing against either of the stops 94 or 97 or applied to the web portion 90 of the flywheels 20 the screening device is set for two screen or two deck operation. When it is desired to add an intermediate screen or deck to the screen body 22 all that is necessary to be done is to take a pair of like 70 balancing rectangular plates 21 and cause their longitudinal edges to bear firmly against the 75

abutments 94 and against which they may be held by means of bolts passing through holes 99. On the other hand, if it is desired to operate the screening device with only one screen 73 or deck 5 in the screen body, the pair of balancing plates is removed from its position just described and similarly associated with the stops 97 as shown in Fig. 6 and held thereagainst by means of bolts passing through other holes 99. A flywheel under the arrangement stated should ordinarily 10 balance when a counter-weight equivalent to a certain number of inch pounds depending upon the weight and arrangement of screen body is placed diametrically opposite the heavy side of 15 the flywheel in line with the key seat. For example, a required counter-weight may amount to 120 divided by 12 equals 10 pounds, if placed at a radius of 12 inches.

The flywheel just described being cast from 20 metal is relatively expensive and therefore the flywheel 120 formed of rolled steel plate and comprising a disk as shown in Figs. 7 and 8 is preferred. This steel plate material makes a flywheel constructed therefrom rather inexpensive 25 as compared to a flywheel cast in the form shown in Fig. 6. The flywheel 120 similarly to the flywheel 20 shown in Fig. 6 is provided with large circular bores 196 which may be of a smaller diameter than the recessed circular bores 198 located in a diametrical line passing through the 30 keyway 197 and which may have their centers on the same circle as the bores 196. The face of a flywheel 120 opposite the bores 198 is recessed, as shown at 200, to receive the heads of bolts 201 35 passing through apertures concentric with the bores 198 within the flywheel, each of said bolts 201 selectively securing a balancing disk 199 of a suitable length or lengths of shafting or disks within the desired bore 198. The bores 196 similarly to the bores 96 of the flywheel 20, shown 40 in Fig. 6, are equally spaced from the diametrical line defined by the centers of the bores 198 and they are likewise equally spaced from a diametrical line at right angles to said diametrical line. 45 The operation of this preferred form of flywheel is apparent from a description of the operation of the flywheel shown in Fig. 6. With two screens 73 within the screen body 22 neither recessed bore 198 will contain a balancing disk 199, while 50 if an intermediate screen is added to the two screens shown within the screen body 22, a balancing disk 199 is inserted in the bore 198 adjacent the keyway 197. On the other hand, if only one screen 73 is contained within the 55 screen body only the other bore 198 will receive a balancing disk 199.

In order to enhance the efficiency of operation of the disclosed screening device having a single, 60 gyratory screen, and for practical reasons, an I-bolt 66 is preferably secured to each corner of the frame 34 to receive the loop portion of a threaded U-bolt 67 carrying disks 68 provided with apertures to receive the leg portions of another inverted threaded U-member 67. The nuts 65 cooperating with the threaded ends of the U-bolts 67 and pressing against the adjacent disks 68 compress a helical compression spring 70 depending upon the weight of the frame 34 and parts 70 carried thereby. A cable 75 is secured to each one of the upper U-bolts 67. The other end of which cable is attached to an overhead support. Should the frame 34 move vertically downward due to 75 unusual shock of falling material on the screen 73 or to improper balancing of the vibrating

mechanism the springs 70 would restrain this movement to a certain degree depending upon their strength and the compression provided therein. The springs 70 effect a very desirable cushioning action on the overhead support and prevent dependent vibration of the frame 34 and therefore also of the screens 73, which it is understood may be perforated plates, with respect to the overhead support for the vibratory screening device.

In explanation of the use of springs 70 it may be stated that while the counter-weights 21 or 199 on the flywheels 20 and 120, respectively, ordinarily take care of all unbalancing due to the weight of the eccentrically carried screens 73 and 15 their carrying and supporting elements, the variations of the load carried on the screens during the operation which cannot be maintained uniform at all times will cause some vibrations to be transmitted to the supporting frame 34 and 20 these are taken care of by the springs 70, instead of being transmitted to the overhead support and from there throughout the building.

In some cases it may be desirable to support the frame 34 resiliently from inclined fixed supports 100 as illustrated in Fig. 11. This may be accomplished by locating an inclined upper telescoping socket member 101 and a lower cooperating telescoping socket member 102 near each of the four corners of the frame and securing 30 these respectively, to the frame 34 and to the spaced supports 100. Helical compression springs 103 one axially positioned within each of the socket members 101 and 102, resiliently support the frame 34 from the supports 100. With either 35 form of resilient support described above, the position of the driving motor 41 and driving elements between it and the eccentric drive shaft 18 on one side of the frame 34 would tend to weigh down that side of the screen frame and 40 position the drive shaft 18 out of the horizontal and thereby effect unequal screening actions in transverse portions of the screens 73. In order to preclude this possibility and to maintain a uniform transverse disposition of the screening 45 material on the screens 73, counter-weights 78 are attached to the web portions of the I-beam 71 opposite the I-beam 71 which directly supports the motor 41. It will be noted that the center of gravity of the counter-weights 78, at the preferred inclination of the frame 34, is in a vertical plane parallel to the axis of the drive shaft 18 and passing substantially through the center of the driving motor, to properly effect said counterbalancing action thereby, since the supporting frame 34 must necessarily be operated in 50 a position longitudinally inclined to the horizontal. 55

A feed hopper 77 shown in dot-dash lines at the elevated or feed end of the gyratory screening device in Fig. 2 may be employed to conduct the material to be graded on to the upper screen 73 whereupon the gyratory action of the screen body 22 will effect the classified grading desired depending as to whether one, two or three or more screens 73 are carried within the screen body.

The disclosed gyratory screening device permits ready dissociation of the eccentric drive shaft and cooperating bearing elements, or in other words, the vibrating shaft mechanism as a unit, from the screen body 22 and from the supporting frame 34. It further includes means for effectively yet readily effecting displacement and fixation of the screen frames within the screen 75

body. The improved flywheels effect and facilitate a selective balancing against the eccentric-carried screen body with the screen body carrying one or a plurality of screen frames. The 5 spring rod support permits of readily adjusting the inclination of the screen body with respect to the supporting frame while permitting in each adjusted position a desired closed circuit vibration of the screen body and therefore also the 10 screens 73 at that end portion of the screens and effectively precludes the relative rotation of the screen body with respect to the frame 34 when the screening device is in operation. The resilient support means for the frame 34 prevents dependent vibration between the supporting members 15 for the screening device and the frame 34 and the counter-weights 78 cooperate with such supporting means for the screening device to maintain the single gyratory shaft of the screening 20 device in the desired horizontal position. Each of these features is conducive of enhancing the efficiency and value of this screening device and is separately set forth in the following claims.

It should be understood that it is not desired 25 to limit the invention to the exact details herein shown and described, for various modifications within the scope of the claims may occur to persons skilled in the art.

It is claimed and desired to secure by Letters 30 Patent:

1. In a vibratory screening device, in combination, a screen frame, an operating eccentric about which said frame may pivot longitudinally and which participates in its support, a frame support for said eccentric, transverse resilient supporting means for said screen frame located at a distance from and generally parallel to the axis of rotation of said eccentric, said means being secured at its ends to said frame support and at its middle to said screen frame and permitting of a closed circuit movement of said screen frame in a longitudinal plane thereof and means for rotating said eccentric.
2. In a vibratory screening device, in combination, a screen member, an operating eccentric about which said screen member may pivot longitudinally and which participates in its support, a frame support for said eccentric, transverse resilient supporting means for said screen member located at a distance from and generally parallel to the axis of rotation of said eccentric, said means being secured at its ends to said frame and at its middle to said screen member and permitting of a closed circuit longitudinal movement of said screen, means connected with said screen member-supporting means permitting of adjustment of the inclination of said screen member with respect to said frame, and means for rotating said eccentric.

3. A gyratory screening device comprising, a frame, vibrating means including a shaft provided with an eccentric, rotatably associated with said frame, means connected with said eccentric and partaking of its motion, a screen member secured to said means, flexible means comprising a rod located remote from and generally parallel to said shaft and secured to said screen member and to said frame, and permitting of a substantially circular movement of said screen member, means connected with an intermediate portion of the rod of said flexible means, permitting adjustment of the inclination of said screen member with respect to said frame, and means for rotating said shaft.
4. A gyratory screening device comprising, a

frame, vibrating means including a shaft provided with an eccentric, rotatably associated with said frame, means connected with said eccentric and partaking of its motion, a screen member secured to said means, means comprising a flexible rod located remote from and generally parallel to said shaft and clamped at an intermediate portion to said screen member and at its ends to said frame and permitting of a closed circuit movement of said screen member, means connected with an intermediate portion of the rod of said remote means, permitting adjustment of the inclination of said screen member with respect to said frame, and means for rotating said shaft.

5. A vibratory screening device, comprising a frame supported at a plurality of points, vibrating means including a shaft journaled to said frame, means connected with said vibrating means and partaking of its motion, a screen secured to said connected means, flexible means positioned generally parallel to and located remote from said shaft and secured to said frame and to said screen, intermediate portions of said flexible means being flexible in directions transversely of said shaft, said means permitting of a closed circuit movement of said screen transversely of said shaft, means connected with said flexible means remote from said shaft permitting adjustment of the inclination of said screen relative to said frame, and means for rotating said shaft.

6. A vibratory screening device, comprising a frame suspended at a plurality of points, vibrating means including a shaft journaled to said frame, means connected with said vibrating means and partaking of its motion, a screen secured to said connected means, means comprising a resilient rod located, remote from and generally parallel to said shaft and secured at an intermediate portion to said frame and at its ends to said screen and permitting of a closed circuit movement of said screen transversely of said shaft, means connected with an intermediate portion of the rod of said means remote from said shaft, permitting adjustment of the inclination of said screen relative to said frame, and means for rotating said shaft.

7. A vibrating screen mechanism, comprising a frame adapted to carry three screens, a shaft having eccentric portions operatively connected to impart vibratory motion to said frame, means for 50 rotatably supporting said shaft and for supporting said frame to permit vibration thereof, unbalanced flywheels secured on said shaft said unbalanced wheels being so proportioned that they effectively counterbalance said frame when it is 55 carrying two screens and being shaped to receive counterweights at two predetermined positions, and counterweights for said unbalanced flywheels said counterweights being so proportioned that when attached to said flywheels at one of said 60 predetermined positions the flywheels become so unbalanced as to effectively counterbalance said frame when it is carrying three screens and when attached to said flywheels at the other of said predetermined positions the flywheels are so adjusted as to effectively counterbalance said frame 65 when it is carrying only one screen.

8. A vibrating screen mechanism, comprising a frame adapted to carry three screens, a shaft having eccentric portions operatively connected 70 to impart vibratory motion to said frame, means for rotatably supporting said shaft and for supporting said frame to permit vibration thereof, unbalanced flywheels secured on said shaft said unbalanced wheels being so proportioned and 75

- having their heavy sides so disposed that they effectively counterbalance said frame when it is carrying two screens and being shaped to receive counterweights at their heavy sides and 5 at their light sides, and counterweights for said unbalanced flywheels said counterweights being so proportioned that when attached to said flywheels at their heavy sides the flywheels become so unbalanced as to effectively counterbalance 10 said frame when it is carrying three screens and when attached to said flywheels at their light sides the flywheels are so adjusted as to effectively counterbalance said frame when it is carrying only one screen.
- 15 9. A vibratory screening apparatus, comprising a supporting frame, a screen vibrating shaft rotatably mounted on said frame, a screen element pivotally carried by said screen vibrating shaft, and resilient supporting means for said 20 screen element including a resilient rod disposed substantially parallel to said shaft and spaced therefrom said rod being attached at its ends to opposite sides of said frame and connected to said screen element near the middle thereof.

10. A vibratory screening apparatus, comprising a supporting frame, a screen vibrating shaft rotatably mounted on said frame, a screen element pivotally carried by said screen vibrating shaft, and resilient supporting means for said screen element including a resilient rod disposed substantially parallel to said shaft and spaced therefrom said rod being attached at one end to said frame and connected to said screen element near the middle thereof. 5

10 11. A vibratory screening apparatus, comprising a supporting frame, a screen vibrating shaft rotatably mounted on said frame, a screen element pivotally carried by said screen vibrating shaft, resilient supporting means for said 15 screen element including a resilient rod disposed substantially parallel to said shaft and spaced therefrom said rod being attached at one end to said frame and connected to said screen element near the middle thereof, and 20 means associated with said rod for effecting adjustment of the inclination of said screen element relative to said frame.

CHARLES S. LINCOLN.
